UNITED STATES PATENT OFFICE.

PETER MAROS, OF WATERBURY, CONNECTICUT.

TRUNK-LID HOLDER.

1,334,546.

Specification of Letters Patent. Patented Mar. 23, 1920.

Application filed October 16, 1919. Serial No. 331,003.

To all whom it may concern:

Be it known that I, PETER MAROS, a citizen of Russia, residing at 285 Highland Ave., Waterbury, county of New Haven, and State of Connecticut, have invented 5 certain new and useful Improvements in Trunk-Lid Holders, of which the following is a specification.

The principal object of this invention is 10 to provide a trunk lid holder adapted to retain the lid securely when in an open position.

Another object is in the provision for 15 readily attaching such devices to any hinged covered container, so as to close within itself, thereby occupying little space, the device being of great strength and of simple construction.

These objects are attained by the novel 20 construction and combination of parts hereinafter described and shown in the accompanying drawings, forming a material part of this disclosure, and in which—

Figure 1 is a perspective assembled view 25 of the device.

Fig. 2 is a transverse sectional view taken on line 2—2 of Fig. 1, and

Fig. 3 is a longitudinal sectional view taken on line 3—3 of Fig. 1.

Referring to the drawings in detail, the 30 numeral 10 designates a rectangular bar having a deep recess 11 formed in one of its sides adapted to receive a movable brace strip 14, having offset reduced end sections, one 35 of which is pivotally secured within the recess 11 by the rivet 15 the opposite end being pivoted within a slot 16, by the rivet 17, passing through a movable block 18, slidably retained within the rectangular tubular 40 bar 19.

Stop elements 21 and 22 are fixed internally of the ends of the tubular bar 19, thereby limiting the movement of the block.

A slot 23, piercing one side of the tube 45 19, permits the entrance and movement of the brace strip 14 and provides means for inclosing same when the trunk is closed, the elements 10 and 19 being rigidly secured to the lid 12 and trunk body 20 by the rivets 13 and 24 respectively.

In operation, the lid 12 is raised vertically with respect to the body 12', this action moving the sliding block 18 outward to the far end of the slot in the bar 19, causing engagement of the projection 18' with a similar but reversed projection 22' of the 50 fixed stop 22, thereby preventing the cover from being moved farther or the block from rising when the cover is open, obviously the block 18 moving to the front and the brace 55 strip 14 becoming partially contained in the slots 11 and 23 when the lid is closed.

Having thus described my invention what I claim as new, and desire to secure by Letters Patent, is—

In a trunk lid holder, the combination 60 with a trunk having a hingedly attached lid, of a bar fixed in said lid transversely thereof, a tubular bar fixed in said body in register with the first named bar, a block slidable 65 in said tubular bar, a projection at one end of said block, a brace strip pivoted in the first named bar at one end and to said block at the other, said bars each having recesses adapted to contain said brace strip 70 when said lid is closed, a pair of stops fixed in said tubular bar limiting the movement of said block, and a projection formed with one of said stops engageable with the first 75 named projection preventing said block from rising from the mentioned recess in said tubular bar.

In testimony whereof I have affixed my signature.

PETER MAROS.
